GEORGE D. GOODRICH, OF CHICAGO, ILLINOIS.

Letters Patent No. 86,148, dated January 26, 1869.

IMPROVED CLAY-MACHINERY.

The Schedule referred to in these Letters Patent and making part of the same.

To all whom it may concern:

Be it known that I, GEORGE D. GOODRICH, of the city of Chicago, in the county of Cook, and State of Illinois, have invented certain new and useful Improvements in Machinery for Working Clay and other plastic materials; and I do hereby declare the following to be a full, clear, and exact description thereof, which will enable others skilled in the art to make and use the same, reference being had to the accompanying drawings, making part of this specification, in which—

Figure 1 is a longitudinal vertical section;

Figure 2, a plan and a side view of the expansion-heads;

Figure 3, a front view, with the expansion-heads removed;

Figure 4, a front view, with the expansion-heads attached; and

Figure 5, a side view of the main head.

Like letters refer to the same parts in all of the figures.

The nature and object of my invention consist in constructing a machine for working clay, or other plastic material, so as to produce enlarged ends, heads, or collars on clay pipe, for sewerage and drainage-purposes, and for forming or enlarging the ends or bodies of cylindrical clay or other bodies formed of plastic material, and in so arranging the parts that there shall be one or more heads or formers moving outward from the centre of revolution of the machine, and the centre of the clay or other cylindrical body to be enlarged.

To enable others skilled in the art to make and use my machine, I will proceed to describe its construction and operation.

A represents a suitable frame-work for sustaining and holding the operative parts.

B represents an adjustable belt or pulley-wheel, by which, or by other suitable-device, motion is imparted to the shaft C.

The shaft C is made hollow, or cylindrical, as shown, and its outer end, Q, is enlarged, as shown, for the purpose of affording room for the extension-arms.

This enlarged portion is not necessarily cylindrical, as arms can be used to make the connection between the shaft C and head, P.

At the outer end of Q a head, P, is attached, the diameter of which will be determined by the size of the pipe or other articles to be applied.

This head, as shown, is provided with four equidistant radial guide-grooves or slots, J, which said grooves J are provided with side slots or grooves, K.

This head, P, when attached at the back, can be made of a single piece, but it will be found more convenient to make it of separate pieces, as shown at fig. 5, not only in forming the slots K, but in putting the parts together.

In that portion of the grooves J which is below K, I insert short blocks, I, as shown at fig. 1, and to these blocks I, I fasten the pieces M, which extend from the outer end of I down toward the centre, as shown.

These parts M are provided with ledges or guides, L, at their sides, fitting the slots K, and they also extend out, so as to fill the remaining portion of the guide-grooves J, and a little distance beyond the face of the head, P.

If desired, the parts I, L, and M, can be made of a single piece, or they may be made separately and fastened together.

To these sliding pieces M, I attach expansive head-pieces N, as shown at fig. 4, which are made in segments, and are made thicker on one side than on the other, as shown at f g, fig. 2, and so attached to M, that when in motion the thin or reduced edge g will be in advance of the other.

To these head-pieces N, at the inner side, I attach segmental projections O, which extend out as far as it is desired to enlarge the pipe or other article. For drain or sewerage-tile, from one and one-half to two inches will be sufficient.

These projections O are attached so that the front or advance ends, k, will be nearer their centre of rotation than the rear ends, i.

The reason for so locating them, and for placing the reduced edges of N in advance is, that in handling clay by machinery, and particularly in expanding it from the inside, a clear, sharp, and well-defined edge for the clay to pass off from is necessary, to give a smooth surface and prevent cracking.

These expansive heads N are operated by a rod or bar, D, which passes through cylindrical shaft C.

At the rear end of this rod there is a stop or button, R, and at the front end a collar provided with arms, E.

To these arms E are pivoted, at c, curved arms a, and to these curved arms a are pivoted, at d, curved arms b, which (b) are pivoted to I, at e.

The reasons for jointing the curved arm a b at d are, that the machine can be made to occupy less space, and also to move with greater power and traverse a greater distance.

Immediately in front of these arms a b is the circular plate or plates G F. This plate is made in two parts, so that the section F, which has the guide-grooves for the arms a b, will always accommodate itself to the position of the arms without moving the spring H. It can, however, be made of one piece, but I prefer it when made in two parts, as shown.

They are held in place, and pressed against the arms a b, by the spring H, which arrangement operates as a guide for such arms, keeping them in place, and yielding, so as to allow the arms to operate freely and effectually, when power is applied, at R, to expand the front. The power is applied at R by a lever or any other suitable means.

In operation, the pipe, in its plastic state, is placed in a suitable trough, or conveyed, in the one in which it was originally formed, to the front of the machine. The rod D is retracted, which brings the projections O as near the centre of the machine as is desired, when

the pipe is brought over them, and against the expansion-heads N, when pressure is applied at R, gradually expanding the projections O, until a head or opening in the pipe, of sufficient size, is formed.

The heads or segments N can be secured to M in different positions, so as to fit the projection O to different-sized pipes or other articles, without changing the expansion or contraction produced by operating the rod D, as shown at h, fig. 3.

It will be obvious that pipes can be enlarged by the use of one of these expansion-heads N, provided with projection O, although not with the same rapidity, and that crocks with straight sides can be made by substantially the same machinery, the only change required being to provide the projections O with oblique grooves or projections, to draw the clay towards the head, and placing the head, P, horizontally.

Heads to tile, for sewerage and draining-purposes, can be made upon the same principle, by using one head, and gradually moving the pipe to the one side of the centre of motion of the machine, as, by such an arrangement of the parts, the movement from the centre is transferred from the machine to the pipe

itself, but it is only a modification of the machine herein described.

Having thus fully described my machine,

What I claim as new, and desire to secure by Letters Patent, is—

1. The combination of the hollow shaft C, rod D, and jointed arms a b, with one or more heads N O, substantially as and for the purposes specified.

2. The plate G F and spring H, in combination with the jointed arms a b and sliding rod D, substantially as described.

3. The presser-head N, constructed with the rear edge or end, f, thicker than the advance edge or end, g, substantially as and for the purposes specified.

4. The projections O, when so constructed and attached that the end h will be nearer the centre of rotation than the end i, so as to prevent cracking or checking the pipes and preserve a smooth surface, substantially as specified.

GEORGE D. GOODRICH.
